UNITED STATES PATENT OFFICE.

OSCAR SCHIMMEL, OF CHEMNITZ, SAXONY, GERMANY.

APPARATUS FOR DISINFECTING.

SPECIFICATION forming part of Letters Patent No. 337,522, dated March 9, 1886.

Application filed July 7, 1885. Serial No. 170,845. (No model.) Patented in France September 14, 1883, No. 157,547; in England June 16, 1884, No. 9,014; in Italy November 26, 1884, No. 17,450, and in Belgium December 15, 1884, No. 67,016.

To all whom it may concern:

Be it known that I, OSCAR SCHIMMEL, of Chemnitz, in the Kingdom of Saxony and Empire of Germany, have invented certain new and useful Improvements in Apparatus for Disinfecting Clothes, Textile Fabrics, Parcels, &c., (for which Letters Patents have been granted to me heretofore by the governments of Great Britain, No. 9,014, dated June 16, 1884; to France, No. 157,547, dated September 14, 1883; Italy, No. 17,450, dated November 26, 1884; Belgium, No. 67,016, dated December 15, 1884,) of which the following is a specification.

This invention has reference to an improved apparatus for disinfecting clothes, textile fabrics, parcels, bales, and other articles by means of steam and hot air; and the invention consists of an apparatus having a jacked disinfecting-chamber and an interior frame or cage in which the articles to be disinfected are placed and exposed to the action of hot air and steam, that are supplied thereto by a set of heating-pipes and a live-steam pipe, the disinfecting apparatus being tightly closed and provided with a valved air-induction pipe and a valved eduction-pipe, as will more fully appear hereinafter, and finally be pointed out in the claims.

In the accompanying drawings, Figure 1 represents a vertical longitudinal section of my improved apparatus for disinfecting clothes and other articles. Fig. 2 is a horizontal section of the same on line $\alpha\alpha$, Fig. 1; and Figs. 3, 4, 5, and 6 are respectively a vertical longitudinal section, a horizontal section, a vertical transverse section, and an end elevation of another modification of the apparatus.

Similar letters of reference indicate corresponding parts.

Referring to Figs. 1 and 2 of the drawings, $\alpha\alpha$ represent a circular wall of suitable non-conducting material. Within the wall $\alpha\alpha$ is arranged a cylindrical disinfecting-chamber, a' , of boiler-iron, which is hermetically closed by a detachable lid, d , that is made hollow and filled with sawdust or other suitable non-conducting material. The lid d is attached to the cylinder a' by means of brackets and clamping-screws $s\,s'$. The lid d is suspended by chains passing over differential pulleys, which latter admit the convenient lifting of the lid.

To the under side of the lid d is attached a perforated cylinder or cage, h , having a perforated bottom and interior cross-bars, r , with hooks r' , for suspending the articles to be disinfected. Below the bottom of the perforated cylinder h is arranged a double set of steam-pipes, kk , which are connected with each other at the ends by bends, and with a steam-supply pipe, k' , having a stop-cock, k^2 . The steam-pipes kk are provided with a number of annular projecting ribs, by which a large heating-surface is obtained for heating the air in the cylinder a' . The water of condensation is conducted from the pipes kk by a pipe, c , to a receiver, c' , having an overflow-pipe, c^2 . The bottom of the cylinder a' is provided with a pipe, b , for draining off the water of condensation. A valve-casing, o , at the lower part of the cylinder a' , is provided with an adjustable valve, o' , for admitting air to the interior of the cylinder a' . The upper end of the cylinder a' is provided with an eduction-pipe, m , having a valve, m' , through which the hot air is drawn off at the upper part of the apparatus. A perforated coil, l , above the heating-pipes kk is connected by a pipe, l' , having a stop-cock, l^2 , with the steam-supply pipe k' , and supplies live steam to the disinfecting-chamber a' . A thermometer, t , is located in the eduction-pipe m , to indicate the temperature at the interior of the apparatus. The steam-pipes kk heat the air at the interior of the apparatus, while the live steam admitted through the perforated coil l acts with the hot air on the clothes or other articles in the chamber and thoroughly disinfects the same.

In Figs. 3, 4, 5, and 6 the disinfecting-chamber a' is formed of a double-walled casing, the walls of which are filled with a suitable non-conductor of heat. The disinfecting-chamber a' is heated by a set of steam-pipes, kk , that are supported by rollers g on bottom rails, g' , as shown in Figs. 1 and 2, which are located at the lower part of the casing. The perforated steam-pipe l supplies live steam to the interior of the chamber a' . A movable perforated bottom, h , is suspended by hangers h' from a horizontal frame, h^2 , which forms a cage with cross-bars r and hooks r' for the articles to be disinfected. The cage $h\,h'\,h^2$ moves by means

of rollers g^2 on top rails, g^3 , of the chamber a' . The front wall of the disinfecting chamber a' is provided with two doors, a^5 a^6 , one below the other, of which the upper door, a^5 , serves 5 for removing the cage h h' h^2 from the disinfecting chamber, while the door a^6 serves for removing the system of heating pipes k k in case the entire apparatus is to be moved.

At the lower part of the side walls of the 10 chamber a' are arranged valved openings o o for the entrance of air when it is necessary to admit the same.

The double-walled casing is so constructed that the walls can be taken apart and put together again in order to facilitate the removal 15 of the apparatus from place to place.

Having thus described my invention, I claim as new and desire to secure by Letters Patent--

In an apparatus for disinfecting, a removable cage or basket having perforated walls 20 and bottom, a cross-bar provided with hooks, and a double lid filled with non-conducting material, in combination with a steam-heated chamber surrounded by non-conducting walls, a perforated live-steam pipe, valved induction 25 and eduction air pipes, and a device for raising and lowering the basket, substantially as described.

In testimony that I claim the foregoing as my invention I have signed my name in presence of two subscribing witnesses. 30

OSCAR SCHIMMEL.
